W. A. CLANTON & R. K. COX,
WIRE STRETCHER,
APPLICATION FILED NOV. 8, 1916.

1,231,493.

Patented June 26, 1917.

UNITED STATES PATENT OFFICE.

WILLIAM A. CLANTON AND ROBERT K. COX, OF WOOD, VIRGINIA.

WIRE-STRETCHER.

1,231,493.

Specification of Letters Patent. Patented June 26, 1917.

Application filed November 8, 1916. Serial No. 130,240.

To all whom it may concern:

Be it known that we, WILLIAM A. CLANTON and ROBERT K. COX, citizens of the United States, residing at Wood, in the 5 county of Scott, State of Virginia, have invented a new and useful Wire-Stretcher, of which the following is a specification.

The present invention appertains to wire stretchers, and aims to provide a novel and 10 improved device for stretching fence wires, although it can be used for various other purposes for which it is adapted.

It is the object of the invention to provide a novel combination wire stretcher, 15 which can be used either for pulling a chain attached to a clamp, or for pulling a single wire toward and around a post or other anchor, the device being of unique construction, whereby it can be converted for either 20 of the purposes indicated.

It is also the object of the invention to provide an improved mechanism of the nature indicated which is comparatively simple and inexpensive in construction, and 25 which is convenient, practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 30 within the scope of what is claimed without departing from the spirit of the invention.

The invention is illustrated in the accompanying drawing, wherein:

Figure 1 is a plan view of the stretcher in 40 position for pulling a chain.

Fig. 2 is a plan view of the device in position for pulling a single wire, portions being broken away.

Fig. 3 is a perspective view of one of the 45 arms.

Fig. 4 is a perspective view of the other arm.

Fig. 5 is an edge view of the lever.

Fig. 6 is a longitudinal section of the link 50 connection for the arms.

The wire stretcher embodies a loop-shaped lever 1 provided with a tapered terminal 2

with which the socket end of a handle 3 is engageable, said handle being of suitable length to permit the proper leverage or purchase to be obtained. A draft member 4 is pivoted, as at 5, between the longitudinal portions of the lever and between the ends of said lever, and has attached thereto a chain or other connection 6 for attachment 60 to an anchor post or other object, whereby the lever 1 can be oscillated about the pivot 5 as a fulcrum.

An arm 7 is pivoted within the lever 1 adjacent one end thereof, as at 8, and said lever has a pin 9 adjacent the pivot 8 to act as a stop for limiting the movement of the arm 7 when swung away from the opposite end of the lever. The arm 7 is provided at its free end with a bifurcated hook or 70 claw 10. A second arm 11 is pivoted within the lever 1, by a removable pin or pivot element 12, at that side of the pivot or fulcrum 5 remote from the arm 7, and the lever 1 has a pin 13 serving as a stop to limit the 75 movement of the arm 11 when swung away from the arm 7. The arm 11 is provided at its free end with a bifurcated hook or claw 14, the hooks or claws of the two arms projecting toward one another or toward the 80 opposite arms.

The arms 7-11 are connected near their pivoted ends by a link 16 composed of telescoping tubular sections 16 and 17 fitting together slidably and provided at remote ends 85 with tongues 18 which are pivoted to the arms by means of removable pivot pins 19. The inner tubular section 17 has a diametrical pin 20 engaged therethrough adjacent that end thereof remote from the tongue 18 90 of said section 17, and the section 16 is provided with longitudinal slots 21 receiving the ends of the pin 20, said slots 21 being arranged adjacent the tongue 18 of the section 16. Said outer section 16 has a diametrical pin 22 engaged therethrough adjacent its other end and working within longitudinal slots 23 of the inner section 17. The pins and slots permit of the relative longitudinal movement of the sections 16 and 17 100 of the link, and a coiled wire expansion spring 24 is disposed within the section 17 and is confined between the pins 20 and 22, whereby the spring tends to separate said

pins. This tends to move the terminal tongues 18 of the link toward one another, whereby to contract the link and swing the arms 7-11 toward one another. The sections of the link can be drawn apart to a limited extent, however, when the spring is compressed, thus permitting the arms 7-11 to separate or move away from one another. The spring 24 serves to swing the arms 7-11 toward one another whereby to properly engage the claws of the arms with a chain 25 which can be attached to a fence wire clamp, that is used for clamping a plurality of fence wires.

15 The arm 11 carries a grip for holding a wire W, and to this end, a plate 26 is riveted or otherwise secured to the arm 11 between the ends thereof, and is provided with a leaf spring or tongue 27 projecting toward the fulcrum or pivot of said arm and providing means for wedgedly receiving the wire to grip the same. This plate has a hook 28 projecting to one side to receive the wire. The hook 28 projects toward the same side of the arm 11 as does the claw or hook 14.

20 A spur or pawl 29 is pivoted, as at 30, to the arm 7 between the ends thereof, and said arm has a V-shaped shoulder 31 for limiting the swinging movement of said spur. The spur 29 projects to one side of the arm 7, or toward the same side thereof as does the claw 10. When the spur 29 is not in use, it can be swung adjacent the arm 7 so as to be out of the way.

25 When the stretcher is used for pulling a chain 25 attached to a wire fence clamp or other object, the chain 6 is connected to a post or other anchor, and the link 15 is attached to the arms 7-11, as seen in Fig. 1. 30 Supposing that the claw 14 engages the chain 25 as seen in said figure, the lever 1 is now swung to advance the arm 7. The link 15 will cause the claw 10 to slide along the chain 25, and the spring 24 will cause said claw 10 to snap past the links of the chain, whereby the claw 10 will obtain a hold on the chain, when the lever 1 has been swung a certain amount. It will be noted that the lever 1 in being swung will move the arm 11 toward the anchor, thus pulling the chain 25. The slots of the claws or bifurcated hooks are adapted to receive those links of the chain which are in substantially the same plane as the lever 1, and said claws are engageable with the other links to obtain a hold on the chain automatically as the lever 1 is oscillated. Thus, after the lever is 45 swung as above indicated, so that the claw 10 is advanced and engaged with the chain 25, the lever is now oscillated in the reverse direction, whereby the arm 7 in being moved backwardly will pull the chain 25 with it, while the arm 11 is advanced. The claw 14 of the arm 11 thus moves against and snaps into engagement with the links of the chain.

50 As the lever 1 is oscillated, the chain 25 will therefore be pulled step-by-step, the claws 10 and 14 alternately engaging with the chain, and the arms 7-11 being reciprocated alternately by the lever 1. Due to the provision of the link 15, the arms 7-11 are operated automatically to engage the chain and move it rearwardly, and it is only necessary for the operator to swing the lever back and forth. The engagement of the claws 55 with the chain is also facilitated by the provision of the stops 9-13 which positively swing the arms into engagement with the chain when the lever 1 is swung the full limit of its movement.

50 When the device is used for stretching a single wire W, as seen in Fig. 2, the link 15 is detached from the arms and removed from the device, and the pivot pin 12 is removed, so that the arm 11 can be reversed, as seen in Fig. 2, after which the pin 12 is reapplied to pivot the arm 11 in reversed position with the hook 28 and claw 14 thereof projecting away from the arm 7. The wire W is applied under the spring or clip 27 to wedgedly engage between said spring or clip and arm 11, whereby the wire is gripped, and the lever 1 is then placed against the post P, as seen in Fig. 2. The lever 1 is then swung to move the lever around the post from the dotted line position in Fig. 2 to the full line position, and even farther if necessary. By thus turning the device around the post, the wire is pulled with the arm 11, for stretching said wire, and to prevent the retrograde movement of the device, the arm 7 is swung toward the post P whereby its spur 29 engages the post and prevents such reverse movement of the device. This will hold the wire in taut condition even when the handle 3 is released. The hook 28 is adapted to receive the wire W when the device is in starting position, as seen in dotted lines in Fig. 2, and the claw 14 is adapted to receive the wire when the device is moved to the full line position in Fig. 2, whereby the wire is properly confined in place, although the wire need not be engaged with the claw 14 if not desired.

100 It is an easy matter to convert the device 115 for stretching either a chain or a wire, as will be apparent from the foregoing.

Having thus described the invention, what is claimed as new is:

1. A stretcher embodying a lever adapted to rest against a post, means for connecting the wire to said lever at one side of the post, an arm pivoted to said lever to project across the opposite side of the post, said arm having a limited swinging movement relative to the lever, and a spur pivoted to said arm and projecting toward the lever to engage the post, said spur having a limited swinging movement relative to said arm.
2. A stretcher embodying a lever, an arm 130

pivoted thereto, a spring tongue carried by said arm and projecting toward the pivot thereof for receiving and gripping a wire, and a wire receiving hook carried by said arm and projecting to one side thereof between the tongue and free end of the arm.

In testimony that we claim the foregoing

as our own, we have hereto affixed our signatures in the presence of two witnesses.

WILLIAM A. CLANTON.
ROBERT K. COX.
